UNITED STATES PATENT OFFICE.

EDMUND C. MORGAN, OF NEW YORK, N. Y.

MINING AND LOADING MACHINE.

1,427,119.

Specification of Letters Patent. Patented Aug. 29, 1922.

Application filed July 15, 1915, Serial No. 39,986. Renewed October 30, 1920. Serial No. 420,821.

To all whom it may concern:

Be it known that I, EDMUND C. MORGAN, a citizen of the United States, residing at New York, in the county of New York and 5 State of New York, have invented certain new and useful Improvements in Mining and Loading Machines, of which the following is a specification.

My invention relates to mining and loading apparatus whereby material is completely severed from a mine wall and then moved back from the mine wall into position for loading. One of the objects of my invention is to provide improvements on the 10 mining and loading machine disclosed in my copending application Ser. No. 864,211, filed Sept. 30, 1914, for an improvement in mining and loading machines, and also has certain features in common with the subject- 15 matter disclosed in my copending application Ser. No. 848,727, filed July 3, 1914, for an improvement in mining machines.

Other objects of the invention will appear hereinafter, the novel combinations and features being set forth in the appended claims.

Referring to the accompanying drawings—

Fig. 1 is a view in side elevation of a mining machine embodying certain of my 30 improvements;

Fig. 2 is a plan view of that portion of the mining and loading machine shown in Fig. 1;

Fig. 3 is a longitudinal sectional elevation 35 taken on the line 3—3 of Fig. 2;

Fig. 4 is a front elevational view of the mining machine showing the cutting mechanism;

Fig. 5 is a rear elevational view of Figs. 1 40 and 2, the conveyer mechanism being shown in vertical section;

Fig. 6 is a front sectional elevation taken on the line 6—6 of Fig. 1 with certain parts omitted and a guide pulley shown in elevation instead of in section;

Fig. 7 is a plan view of the extension of the conveyer mechanism from the rear portion of the construction shown in Figs. 1 and 2;

Fig. 8 is a side elevational view of Fig. 7, being broken away at the right to indicate the continuation of the broken away portion at the left of Figs. 1 and 2;

Fig. 9 is a sectional elevational view of

the construction shown in Fig. 8 taken on 55 the line 9—9 of Fig. 7.

Fig. 10 is a cross-sectional elevation of Fig. 7 on the line 10—10 thereof looking in the direction of the arrows, with the rope and its attachment to the conveyer belt 60 omitted;

Fig. 11 is an enlarged plan view of mechanism for connecting the loop cutter with the conveying belt;

Fig. 12 is an enlarged sectional elevation 65 of spring pressed devices associated with the conveyer belt as shown in Fig. 3 for engaging the mined material when being moved to loading position;

Fig. 13 is a plan view partly in section of 70 the loop chain cutter mechanism;

Fig. 14 is a side elevation of a portion of the loop chain cutter to show the alternate positions of individual successive cutters;

Fig. 15 is a cross sectional view of the 75 chain cutter and a portion of the mechanism for holding and guiding the same;

Fig. 16 is a side elevational view of a part of the upper right hand portion of the construction shown in Fig. 4;

Fig. 17 is an enlarged front elevation of the upper right hand portion of Fig. 4 to more clearly show the mechanism for transmitting power to the loop chain cutter;

Fig. 18 is a plan view of Fig. 17 to show 85 the spur and bevel gearing indicated by the dotted circles in Fig. 17;

Fig. 19 is a sectional view of Fig. 17 on the line 19—19 and looking in the direction of the arrows; and

Fig. 20 is a sectional elevation of Fig. 18 on the line 20—20 and looking in the direction of the arrows.

The operating parts of the mining and loading machine shown in the drawing are 95 mounted upon a frame 21 which may be of open-work construction and rectangular in form, as illustrated in Figs. 1 and 3. This main frame of the machine is preferably made of structural steel to facilitate its construction and reduce its weight to a minimum without detracting from its strength. The lower side longitudinal members 22, 22' are rigidly connected together by the crosspieces 23, 24 and 25, as shown in Figs. 100 2 and 3. Extending upwardly from each corner of the rectangular base frame thus constructed, are uprights 26, 26' and 27, 27',

as shown in Figs. 1 and 3. The upper ends of these corner uprights are connected by crosspieces 28 and 29 and by the longitudinal members 30, 30', as shown in Figs. 1 and 5 3. As shown in the drawings, the various longitudinal and cross members of the frame 21 are preferably constructed of angle-beams or structural steel L-shaped in cross section. This main frame forms a very solid and substantial structure which may be braced and strengthened as desired, as by means of cross members of the loading apparatus hereinafter described, and by means of the crosspiece 31 (Figs. 1 and 3), which also 10 supports a bracket 32 for the guide pulley 33. It will be evident that the structural frame-work comprising strengthening members L-shaped in cross section, affords a ready means for efficiently supporting the 15 various operating parts directly as well as in its entirety.

Pivoted to the upper ends of the forward uprights 27, 27' of the main frame, at 34, 34' respectively (Figs. 1 and 3) is a supplemental frame 35 extending entirely across the machine, as shown in Fig. 2. This supplemental frame 35 is provided with two forwardly extending arms one, 36, near the central portion of the supplemental frame, 30 and the other, 37, near one end thereof. The forwardly extending arms 36 and 37 are provided with journal bearings 38 and 39 for the transverse shaft 40, which is also provided with the journal bearings 41 and 35 42 for supporting the chain cutter frame 43.

It should be noted that while the transverse shaft 40 extends into the journal bearing 42, it serves merely as a support for the cutter frame 43, so far as that portion there- 40 of adjacent the journal bearing 42 is concerned. The journal bearing 42 is rigidly connected to the vertical plate 44 which is rigidly connected, as indicated at 45, to the upper surface of the chain cutter frame 43.

45 Rigidly connected to the vertical plate 44, is an additional vertical plate 46 grooved on its upper peripheral portion for receiving the rope 56, its lower edges having the contour indicated at 48 in Fig. 1. The seg- 50 mental plate 46 is connected rigidly to the vertical plate 44 by the intermediate support 49, so as to space the segmental plate from the plate 44 and provide an intermediate space for the pulley 50 which is 55 pivotally mounted on the vertical plate 44, as by means of the bolt 51, which may be held in adjusted position by the nut 52.

Another pulley 53 is mounted on a bolt pivot 54 which is held in adjusted position 60 by the nut 55. The pulleys 50 and 53 are preferably mounted in the same plane and the upper groove in the segmental plate 46 so arranged as to be in direct alinement with the peripheral groove of the pulley 53 adja- 65 cent the same. Both the pulleys 50 and 53,

as well as the upper portion of the segmental plate 46, are grooved to receive the feeding rope 56 which extends downwardly from the segmental plate 46 into the groove of the pulley 57 which is pivoted at 58 to an extension 70 59 of the main frame.

The mechanism for transmitting power to the feed rope 56 comprises a grooved drum 60 on which it is wound, as shown in Fig. 2. This winding drum 60 is secured to a shaft 75 61 supported on an extension of the main frame, as shown in Figs. 1, 2 and 5. To the shaft 61 of the winding drum 60, is secured a large gear wheel 63 which meshes with a pinion 64. To the shaft 65 to which the 80 pinion 64 is secured, is secured a large gear wheel 66 which meshes with a pinion 67, as shown in Fig. 2. The gear 66 may be held by the collar 68 and set screw 69 in proper position.

85 While the shafts 61 and 65 may be rotatable, I prefer to secure them rigidly in position by means of the nuts 71 between the plates 62 and 62'. In such event the winding drum 60 is rigidly secured to the large 90 gear 63 and both are mounted loosely on the shaft 61. In the same manner, the pinion 64 is rigidly connected to the large gear 66 and both mounted to rotate loosely on the shaft 65. The pinion 67 is connected rigidly 95 to the sprocket wheel 72 by means of the sleeve 73 mounted loosely on the reduced portion 65' of the shaft 61. An endless sprocket chain 74 is connected between the large sprocket wheel 72 and a driving 100 sprocket 75 mounted loosely on the transverse shaft 76, which is journaled in bearings 77 and 78, as shown in Fig. 5. The bearings 77 and 78, as shown in Fig. 5, are respectively carried by the brackets 79 and 80 rigidly secured to the lower longitudinal members 22 and 22' of the main frame.

105 The mechanism for transmitting power to the transverse shaft 76 comprises sprocket gearing 81 connected between the shaft 76 110 and the shaft 82. I prefer to rigidly connect the shaft 82 to the bracket 83 on top of the electric motor frame 84. The sprocket gearing 81, as shown in Fig. 3, comprises an endless sprocket chain 81' meshing with a large sprocket wheel 85, keyed to the shaft 76 and also meshing with a small sprocket wheel 86, mounted loosely on the shaft 82 but rigidly connected by the sleeve 87 (Fig. 2) to the large gear wheel 88 which meshes 120 with the pinion 89 on the motor shaft 90 of the electric motor 84.

115 The electric motor 84 is supported by the cross angle-beams 23 and 24, as shown in Fig. 3, and may be held securely in place 125 on the main frame by means of the bolts 91, 91' and nuts 92, 92' engaging the retaining strip 93 at the forward portion of the motor, as shown in Figs. 2 and 5. Extending from the rear end of the frame of the electric mo- 130

tor, is a small bracket 94 provided with an opening 95 (Fig. 2) to receive the bolt 96, the lower end of which is connected at 97 to the cross-beam 23, as shown in Fig. 3, where-
5 as its upper end is provided with a nut 98.

The controller 99 for the electric motor 84 may be mounted on the upper surface of the motor frame and provided with a suitable manual operating lever 100 for actuating the 10 usual and well-known reversing switch and rheostat mechanism for starting, stopping and reversing the electric motor whenever desired.

Whenever the electric motor is operated, 15 motion is transmitted to the transverse shaft 76 through the gears 88 and 89 and the sprocket gearing 81. The sprocket wheel 75 being mounted loosely on the shaft 76, no motion will be transmitted to the gearing 20 connected to the winding drum 60 until the clutch 101 is operated by means of the lever 102, which is pivoted at 103 to a bracket attached to the vertical portion of the cross angle-beam 24, as shown in Fig. 2. When the 25 electric motor 84 is operated in the proper direction, and the clutch 101 is thrown in by means of the lever 102, motion will be transmitted through the sprocket 74 through gears 67, 66, 64 and 63 to the winding drum 30 60. It should be noted that this gearing is reduction gearing, so as to secure a slow rotation of the winding drum 60 and thus obtain a feeding motion of the rope 56, because it is this rope which, upon being 35 pulled slowly, feeds the chain cutter frame 43 from its initial cutting position a short distance back of that shown in Fig. 1, upwardly approximately through a semi-circle. As shown in Fig. 1, the feed rope 56 ex- 40 tends forwardly from the under surface of the winding drum 60 to the pulley 57 over which it is directed upwardly into the groove 104 (Fig. 4) of the segmental frame 46, which is rigidly attached to the chain cutter 45 frame 43. The rope 56 then extends around the groove 105 (Fig. 4) of the pulley 53 (Fig. 1) and thence upwardly into the peripheral groove of the pulley 50 from which the rope 56 extends downwardly into a 50 groove 106 (Fig. 2) in the rearward extension 107, supported near the outer end of the chain cutter frame 43. The rope 56 extends transversely from the extension 107 with respect to the main frame, and is guided 55 around the curved strip 108 to the attachment 109, where the rope is doubled on itself and firmly connected to the conveyer belt 110, as shown in Fig. 11. Not only is that portion of the rope 56 that is doubled on 60 itself securely riveted by the attachment 109 to the belt 110, but it is also riveted to the rectangular plates 111, which act as stops for limiting the movement of the belt 110 toward the triangular plates 112 and 113, as shown 65 in Figs. 3 and 11. The plates 112 and 113

are riveted, as indicated at 114 and 115 to the curved strips 108 and 109, the lateral ends of which are riveted at 116, 116' to the eyes 117, 117' which receive the U-shaped hinge bars 118, 118' which are securely 70 riveted as indicated at 119, 119' to the chain cutter frame 43 (Figs. 3 and 11). It should be noted that the curved strips 108 and 109, particularly that designated 108, are of such thickness as to space the plates 112 and 113 75 apart sufficiently to allow the rope 56 to slip freely between said plates. Therefore, whatever position the belt 110 may occupy at the time that the winding drum 60 is rotated in clock-wise direction, as viewed in Fig. 1, the 80 belt 110 will be moved until it occupies the position shown in Fig. 11, where the abutment 111 will strike against the plates 112, 113 and prevent further movement of the belt relatively to such plates. Further motion of the rope 56 around the extension 107 and around the pulleys 50 and 53 over the groove of the segmental plate 46, will thereby be prevented, and when the winding drum 60 is continued in its rotation in the manner 85 stated, the chain cutter frame will be moved on its pivotal supports 41 and 42 in an anti-clockwise direction, as viewed in Fig. 1, toward the mine wall.

In order to adjust the position of the chain cutter frame, I provide an adjustable support for the supplemental frame 35. This supplemental frame 35 being pivoted at 34, 34', as shown in Figs. 1 and 3 is movable up or down, and when such motion is effected 100 the chain cutter frame is carried with it. Pivoted at 120, to the upright 27, as shown in Fig. 1, is a U-shaped support 121 through the arm 122 of which extends a screw-threaded rod 123 which is pivoted at its upper end 105 at 124 to the supplemental frame 35, at one side thereof, as shown in Fig. 2. At the other side of the supplemental frame, I prefer to pivot at 125 a diagonal bracing bar 126 which is slotted at 127 at its lower 110 end portion to receive the bolt 128 extending laterally from the upright 27', so that by means of the nut 129 the bracing bar 126 may be secured firmly in adjusted position.

When it is desired to adjust the elevation 115 of the chain cutter frame 43, the nut 129 is loosened to free the bracing bar 126 at one side of the machine. The nut 130 at the other side of the machine is loosened whether the chain cutter frame is to be lifted or lowered. By means of the nut 131, either by turning the same back or tightening up on the same, the chain cutter frame may be moved as desired. If the nut 131, after the nut 130 has been turned back, is itself moved 120 in the opposite direction, the weight of the parts suspended from the supplemental frame 35 will immediately lower the same so that the nut 131 always remains in contact with the arm 122. By tightening up on the 125 130

nut 131, the supplemental frame 25 is lifted and with it the chain cutter frame 43, until the desired position is reached. The nut 130 is then again brought against the 5 arm 122 to act as a lock nut, so far as holding the cutter frame in adjusted position is concerned, while the machine is not operating, but upon the return of the chain cutter frame to initial position, the resistance with 10 which it may meet may cause a thrust on the nut 130. Furthermore, after the position of the chain cutter frame has been adjusted by movement of the nuts 130 and 131 in the manner stated, the nut 129 is again brought 15 against the brace bar 126 on the other side of the machine, to firmly brace the supplemental frame in both directions during operation of the chain cutter, and restoring the same to initial position. While I prefer the brace 20 bar 126 at one side of the machine, it should be understood that the adjusting mechanism shown in Fig. 1, connected between the pivotal points 120 and 124, may be duplicated 25 on the other side of the machine.

25 The loop chain cutter 132 is mounted on the chain cutter frame 43, as shown in Fig. 4, and is guided at the outer and lateral edges of the frame 43 and around the outer corners thereof in the manner shown in Figs. 30 3 and 15, wherein the U-shaped frame 133 is provided with grooves 134 for receiving the links 135, the outer links 136 being greater in width and bearing against the forward edges of the plates 133 and 137. These 35 plates 133 and 137 engage the chain cutter frame 43, as indicated in Fig. 3 and may be secured in position in any desired manner. It should also be observed that the cutters 138 and 139 may be of different sizes and extend in various directions toward the center of the chain and laterally therefrom. Preferably the cutters are provided with angular extension plates 140 engaged by plates 141 and held in position by the nuts 142 threaded on the bolts 143 which extend through the 40 links 136, 144 and 134 and are provided with heads 145 at their opposite ends and cross slots 146 for receiving a screw-driver. I prefer to provide the laterally extending cutters 139 so as to produce a kerf of sufficient 45 width to permit the cutter frame 43 to freely pass into the kerf as it is produced. (See Fig. 3.) As shown in Fig. 4, a curved guide 147 is provided for the upper left hand corner of the chain cutter. This curved guide 50 147 serves to lift the slack portion of the chain upwardly from the trough 148 and direct it into the guideways shown in Figs. 3 and 15.

55 As shown at the upper right hand portion of Fig. 4, a sprocket wheel 149 meshes with the sprocket chain 132 and is pivoted at 150 for driving rotation in an anti-clockwise direction. As shown in Fig. 19, the 60 sprocket wheel 149 is secured to a gear 151

which meshes with an intermediate gear 152, as shown in Fig. 20. The bearing shaft 150 is mounted between a portion of the frame 43 and a bracket 153 which is bolted at 154 to the arc-shaped trough 148. The shaft 150 70 is in reality a bolt provided with a head 155 fitting against the frame 43 and having a screw threaded portion 156 at its other end for receiving the clamping nut 157.

As shown in Fig. 20, the intermediate gear 75 152 meshes with the gear 158 which is rigidly connected to the bevel gear 159, the latter meshing with the bevel gear 160, as shown in Fig. 18.

The bevel gear 160 is keyed to the shaft 80 161 which is mounted in a bearing 162 bolted at 163, 163' to the auxiliary frame 43' which is securely fastened at 164 and 165 to the circular trough 148. The shaft 161, as shown in Figs. 4 and 17, extends laterally to receive 85 the large sprocket wheel 166 which is connected by a sprocket chain 167 directly to a sprocket wheel 168 on the shaft 90 of the electric motor 84. It is therefore evident that when the electric motor is operated, 90 power will be transmitted through the sprocket chain 167 and the gears 160, 159, 158, 152 and 151 to the sprocket wheel 149, which in turn actuates the loop chain cutter 132. It should be observed that 95 although the shafts 161 and 40 are in alignment with each other, as viewed in Figs. 2 and 4, said shafts are independently mounted. The shaft 40 is preferably held rigidly in position with respect to the arms 100 36 and 37 by the clamping members 38 and 39, so that the ends of the shaft 40 will serve as bearing supports for the bearings 41 and 42 from which the cutter frame is suspended. The shaft 161 is mounted in the long bearing 105 162, as shown in Figs. 18 and 19, independently of the shaft 40, so that the loop chain cutter 132 may be operated at any time, irrespective of the position of the chain cutter frame 43 or whether it is moving or not. 110

As shown in Figs. 4 and 18, the auxiliary frame 43' is rigidly connected to the bearing support 41 so that the sprocket wheel 149, being mounted in the auxiliary frame 43', always retains the same relative distance from the supplemental frame 35. That portion of the chain cutter frame which guides the chain cutter during the cutting operation, is adjustable with respect to the supporting bearings 41 and 42. This 115 adjustment is secured by providing the chain cutter frame 43 with flat plate extensions 169, 169' as shown in Figs. 3, 4, 16 and 17. At the right hand portion of the machine, as shown in Fig. 4, the extension plate 169' fits into a rectangular recess in the frame 43' and is held in adjusted position by bolting the plate 170 against the same, as shown in Figs. 16, 17 and 18. In order to strengthen the guides for the plates 169, 169' additional 120 lat- 130

eral guideways consisting of vertical flat plates 171, 171', as shown in Figs. 1, 2, 3, 16, 17 and 18, are provided.

At the upper left hand portion of Fig. 4 5 the vertical extension plate 169 may be secured in adjusted position by the bolts 172, 172'; if desired, however, the bolts 51 and 54, as shown in Figs. 1 and 2, may be used 10 to secure the vertical plates 171 and 169 firmly in adjusted position, but in such event the pulleys 50 and 53 will become fixed and will necessitate the rope 56 slipping around the same as it does around the segmental plate 46.

15 The mechanism for adjusting the radial length of the chain cutter frame from its pivotal axis, is primarily for the purpose of adjusting the radius of the kerf to be cut in the mine wall, although such adjusting 20 mechanism may also be used to some extent for taking up the slack in the chain cutter 182. When the radial length of the chain cutter frame is to be varied to some extent, one or more links may be taken out 25 or inserted in the chain, as occasion may require. When the chain cutter frame is to be lengthened, the same may first be moved forward from its initial position a short distance and then the fastening mechanism for the plates 169, 169' loosened to 30 permit the latter to slide to a lower position, or until the frame meets the floor of the mine. It may be preferred, however, both for lengthening and shortening the cutter 35 frame, to provide a plurality of manually operated screw jacks suitably located beneath the lower horizontal portion of the cutter frame. Assuming the chain cutter frame to be entirely clear of the mine floor 40 when in initial position and when moved into the mine, it is evident that by loosening the adjusting mechanism for the plates 169, 169', the nuts 130 and 131 may be so operated as to lift or lower the supplemental 45 frame 35 on its pivots 34 and 34' so as to move the shaft 40 approximately midway between the roof and floor of the mine chamber. In this way, the floor of the mine will take the weight of the chain cutter frame 43, 50 while the pivot shaft 40 and the parts carried thereby may be moved up or down while the fastening mechanism for the plates 169, 169' is in released position. It is also obvious that in this manner the radial length 55 of the chain cutter frame may be readily varied, links of the chain cutter being inserted or removed as may be necessary. After the shaft 40 has been located approximately midway between the floor and the 60 roof of the mine, the fastening mechanism for the plates 169, 169' may again be operated to securely clamp the parts 169 and 171, and 169', 170 and 171' in fixed relative position. The nuts 130 and 131 may also be 65 locked in position and the ceiling jack 173

secured firmly in position. This ceiling jack 173 is shown in Figs. 1 and 2 pivoted at 174 to the upper surface of the supplemental frame 35, but by reason of the firmly secured brace 121, 123, it acts on the main 70 frame 21 as well as on the supplemental frame 35.

As shown in Figs. 5 and 6, the lower longitudinal angle-beams 22 and 22' may be provided with sliding shoes 175, 175' to facilitate movement of the mining machine over the mine floor as well as to protect the frame of the mining machine.

25 The loading apparatus comprises an inclined chute 176 which extends entirely across the main frame of the mining machine, as shown in Figs. 1, 2, 3 and 6. The inclined chute 176 is preferably composed of side angle strips 177 and 177' and intermediate longitudinal strips 178, spaced apart 80 from each other and from the angle strips 177 and 177', as shown in Figs. 2 and 6. The lateral angle plates 177 and 177' and the intermediate strips 178 are held together by a series of transverse strips 179 which are 85 riveted thereto. The rear end of the chute 176 rests on the upper transverse angle-beam 28, as shown in Fig. 3, while the forward portion rests on the screw-threaded rod 180, as shown in Fig. 1. Preferably this 90 screw-threaded rod 180 is so located as to engage one of the transverse angle strips 179. The rod 180 passes through an opening in the bracket 181 which is securely 95 fastened to the upright 27 of the main 100 frame. By means of the nuts 182 and 183, the position of the screw-threaded rod 180 may be adjusted and consequently the lower portion of the chute 176 may be lifted or lowered as desired. As shown in Fig. 2, 105 the adjusting devices, comprising the screw-threaded rods 180 and 180' are located on opposite sides of the main frame respectively immediately above the lower longitudinal angle-beams 22 and 22'.

110 As shown in Figs. 1, 2 and 3, brackets 184, 184' are fastened to the upper longitudinal beams 30, 30' by means of the angle plates 185 (Fig. 2), these brackets serving as pivotal supports at 186, 186' for the 115 lateral walking beams 187 and 187'. The forward ends of these walking beams 187, 187' are held in adjusted position by the nuts 188, 189 and 188', 189' which are threaded on opposite sides of the beams on 120 the screw-threaded rods 190, 190' respectively pivoted at 191 and 191' to brackets 192 and 192' securely fastened to the uprights 27 and 27' as shown in Figs. 1 and 3. Obviously by operating the nuts 188, 189 and 188', 189', the walking beams 187 and 187' may be varied in position as desired, that is to say, lifted or lowered on the 125 pivotal supports 186 and 186'.

130 As shown in Figs. 8 and 9, the walking

beams 187 and 187' extend toward the rear from their pivotal supports 186 and 186' a distance approximately equal to the forward extensions shown in Figs. 1 and 3. The 5 rearward extensions serve as supports for the transverse Z-beams 193 and 194, to which is riveted the chute 195, as shown in Fig. 7. This chute 195 is a rear continuation of the chute 176 and is similarly constructed, 10 being provided with longitudinal lateral angle strips 196, 196' and intermediate strips 197 spaced apart from each other and from the angle strips 196 and 196' and held together by the transverse strips 198 and 199. 15 The cross strip 199 is the one at the rear end of the chute 195, as shown in Fig. 7, and is provided with rearwardly extending brackets 200, 200' which serve as bearings for the shaft 201, which also extends 20 through the bearings in the brackets 202 and 202' extending rearwardly from the longitudinal angle strips 196 and 196'. The shaft 201 carries three drums, 203, 204, and 205 which serve as direction pulleys for the 25 flexible belt 110 when the latter is pulled around the same. The middle drum, 204, acts also as a direction pulley for the driving rope 206 which is securely fastened at 207 to the rear end of the flexible belt 110, 30 as shown in Figs. 7 and 9.

As shown in Figs. 7 and 8 the lateral rear portions of the chute 195 are provided with adjustable jacks for engaging the lateral faces of the mine wall, as shown by the 35 dotted line position of one of the jacks in Fig. 10. These chute jacks are preferably constructed to have loops or U-shaped rods 208, 208', the ends of which are slideable in sockets 209, 210 and 209', 210' and held in 40 adjusted position by means of the set screws 211, 212 and 211', 212'. The sockets 209, 210 and 209', 210' are provided with right angle extensions 213, 214 and 213', 214' extending in opposite directions, as shown in 45 Figs. 7 and 8, and fitting in bearings 215, 216 and 215', 216'. Set screws 217, 218 and 217', 218' may also be provided for holding the jacks in laterally extending position or in any other position. By adjusting the 50 lengths of the chute jacks so as to be somewhat less than the width of the mine chamber, the jacks will act as buffers to minimize the blows of the same against the mine wall as the entire mining and loading machine is 55 moved forward for continued mining operations. The chief function, however, of the chute jacks is to steady the rear chute section 195 by holding it against lateral vibration during the loading operation. 60 In addition to the forward jack 173, ceiling jacks 219, 219' (Fig. 5) may be pivotally mounted at 186, 186' in common with the walking beams 187 and 187', although having a pivotal movement independently 65 thereof. It will thus be seen that by means

of the ceiling jacks 173, 219 and 219', the main and supplemental frames may be securely held in position during the mining and loading operations; and during the loading operation the wall jacks 208 and 208' 70 may be relied upon to brace the rear chute 195 against lateral vibration. When the ceiling jacks are released and the rear chute jacks swung downwardly partially or entirely, the entire mining machine may be 75 pushed forwardly into position for making a new cut in the mine wall. When the machine is to be moved back from the mine wall connection for the pulling chain may be made at the handle or eye 220 at the rear 80 lower portion of the main frame, as shown in Figs. 1, 2 and 3.

After all the parts have been properly adjusted and the ceiling jacks operated to secure the machine firmly in position, the controller 99 may be operated to secure rotation of the electric motor in the proper direction to rotate the sprocket wheel 149 in the direction to move the chain cutter in cutting direction. When the electric motor 90 is started, the chain cutter begins to operate immediately, but it will not be swung upwardly from the position shown in Fig. 1 until the clutch 101 (Fig. 2) is thrown in. When this is done, the winding drum 60 is 95 slowly rotated to gradually move the cutter chain forward and make a U-shaped kerf in the mine wall in order to completely sever therefrom a crescent shaped or semi-cylindrical shaped piece of material. As the 100 loop chain cutter is gradually moved forward, it pulls with it the lower end of the conveyor belt 110. As shown in Fig. 11, there are pivotal connections at 118 and 118' between the cutter frame 43 and the triangular plates 112 and 113 (Fig. 3), and flexible connections by reason of the rope 56 between the plates 112, 113 and the belt 110. The dimension of the triangular plates in alignment with the belt is such as to not 105 interfere with the free movement thereof into the curved kerf 221 (Fig. 3) produced in the mine wall. The belt 110 being flexible may also enter the kerf 221 freely. As hereinbefore explained, when the stop 111 fastened to the rope 56 engages the plates 112, 113, and the pull on the rope 56 is continued, the chain cutter and its frame will be swung forwardly while being pivotally supported by its shaft 40 in the bearings 38 110 and 39 at the forward ends of the arms 36 and 37 respectively of the supplemental frame 35 (Fig. 2). So far as this operation is concerned, the swinging motion is the same as if the rope 56 were fastened securely 115 to the right hand end of the segmental plate 46 (Fig. 1).

At that end of the belt 110 adjacent the chain cutter frame 43, I prefer to locate a plurality of pawls 222, as shown in Figs. 2, 120 130

3, 4 and 11. The connection of each of these pawls with the belt 110 is shown more clearly in the enlarged view designated Fig. 12. The pawls 222 are provided with sharp noses 223 at their upper ends and are pivoted at 224 at their lower ends. The upward movement of each pawl 222 is limited by its rear end 225 and it is held in such position by the spring 226 when no material engages the pawl. Each pivot block 227 is firmly secured to the cross plate 228, which in turn is connected to the rear end of the belt 110 by the clamping plate 229 which may be held in the position shown in Fig. 12 by the screws 230. By means of this construction, the connections between the belt 110 and the chain cutter frame may be entirely of metal, including the rope 56, whereas the belt 110 may be made of leather, rubber, or woven fabric, where greater flexibility is desired, although I prefer to use sheet metal for the belt 110 on account of its greater strength and durability. The upwardly projecting pawls 222 do not interfere with the entrance of the belt or the connections between the same and the chain cutter frame. The springs 226 press the pawls constantly upward, so that as soon as the motion of the chain cutter frame is reversed, the pawls will grip the material and carry the same back with the belt. When the clutch 101 is thrown into released position by the action of the lever 102 (Fig. 2) the chain cutter frame 43, together with the piece of material severed from the mine wall, is free to descend.

In order to secure the return movement of the belt 110 together with the material held on the same by the spring pressed pawls 222, power is transmitted to the winding drum 231, which is mounted loosely on the transverse shaft 76, as shown in Fig. 2. When the electric motor 84 is in operation, the shaft 76 is being rotated through the sprocket gear 81 (Figs. 2 and 3). Pivoted at 232 on a bracket 233 extending forwardly from the electric motor frame, is a manual lever 234 the short arm of which is arranged to operate the clutch 235 into driving engagement with the winding drum 231 so as to transmit motion from the shaft 76 to said drum. When the drum 231 is thus positively rotated, a pull is exerted on the rope 206 which extends around the drum 204 at the rear end of the rear chute 195, to the connection 207. This connection may be similar to that of the forward end of the belt on which the pawls 222 are mounted, but having a transverse metallic plate 236 clamped to the belt 110 by the clamping plate 237 which is fastened to the transverse plate 236 by the screws 238. It will thus be seen that when the drum 231 is rotated in the proper direction, the belt 110 will be pulled up the chute 176 and

along the rear chute 195 while the severed material is being held on the belt by the pawls 222. At the same time, the chain cutter frame is being restored to initial position. While the severed semi-cylindrical or crescent shaped block of material cut from the mine wall may be divided by breaking into various pieces due to its own weight, I contemplate removing the material by the loading apparatus in large blocks. It should also be observed that although the machine is capable of severing the material entirely from the mine wall before it is loaded, the cutting operation may be discontinued before the block of material is completely severed and the spring pressed pawls relied on to break the cut material from the mine wall when the drum 231 is actuated to exert a strong pull on the rope 206 and through the belt and its connections, to the chain cutter frame, to move the same back toward initial position. For instance, half of a semi-cylindrical or crescent shaped block of material may be cut out and removed, first by making a cut substantially halfway toward the ceiling and breaking away the cut out portion and loading it, and then completing the operation by severing the remaining material and loading that. If at any time material should slip back on the belt 110, it would be caught by the pawls 222, the number of which may be increased as desired.

While I prefer to use the pawls 222, they may be omitted where the inclined chute 176 may be arranged so that the angle or repose will always keep the material on the belt and not permit it to slide back. The spring pressed pawls are also preferable to assure the ripping of the material from the mine wall, or its complete severance therefrom, so that when the belt is started back, the material will go with it.

It is evident that after the block of material has been severed from a mine wall and the chain cutter brought back to the position shown in Fig. 3, the material in engagement with the pawls has not as yet been moved a sufficient distance back from the mine wall. I therefore provide means for continuing the rearward motion of the belt 110 even after the chain cutter frame has been brought to rest. In order to limit the rearward motion of the chain cutter frame, the lower longitudinal angle-beams 22 and 22' may be extended forward into such position as to be engaged by the lower portions of the chain cutter frame 43. If desired, however, limit buffers may be extended forward from the uprights 27 and 27' to engage the edges of the plates 171 and 171'.

When the chain cutter frame is held from further backward movement in the manner indicated, continued pull on the rope 206

and on the belt will exert a pull on the rope 56 and cause it to slide around the curved plate 108 and along the plate 171 (Fig. 1) around the pulleys 50 and 53 and around the 5 segmental plate 46, assuming that the drum 60 is free to rotate by the release of the clutch 101.

In order to assure that the the clutch 101 will be in released position when the pull 10 on the rope 56 from the belt 110 is exerted, I have provided a mechanical interlocking 15 connection between the operating levers 102 and 234 of the clutches 101 and 235 respectively. This interlocking connection, as 20 shown in Fig. 2, comprises an interconnecting rod 239 pivoted at 240 to the short arm of the lever 234 for the clutch 235. The 25 other end 241 of the rod 239 extends to a position where it slides through a fixed 30 bracket 242 and is obstructed by the hub portion 103 of the operating lever 102 for the clutch 101, except when the clutch 101 is in released position, when the hole 243 in the hub 103 registers with the opening 25 in the bracket 242. When this occurs, the 35 rod 239 can be moved into the opening 243. It will thus be seen that not until the clutch 101 is fully released can the lever 234 be operated to throw in the clutch 235, and 40 when the latter clutch is thrown in the clutch 101 is locked against being thrown in. Therefore, before the belt can be operated to restore the cutting mechanism to 45 initial position, the clutch 101 must be fully released and after it is once released it cannot be again thrown in so long as the drum 231 is operating to exert a pull on the rope 206, the belt 110 and the rope 56. It is 50 therefore evident that whenever pull is exerted on the rope 56 to unwind the same from the drum 60, the latter is always free, without any danger of having power transmitted thereto from the shaft 76 in the opposite direction. The continued rearward 55 motion of the belt 110 will take the material out of the inclined chute 176 onto the rear chute 195 and over the rear end thereof to dump the same into mine cars immediately below the rear chute. In this way 60 the middle drum 204 will cooperate with the drums 203 and 205 to maintain the belt 110 in proper form, even after the belt has been moved under the chute 195 throughout a considerable portion of its length, or 65 until its connection 207 approaches the direction pulley 33 (Fig. 3).

While the forward feeding motion of the chain cutter frame during the operation of the chain cutter should be comparatively slow, as determined by the reduction gearing 63, 64, 66, 67 (Fig. 2), the return motion of the chain cutter frame and the movement of the conveyer belt during the loading operation is at a comparatively rapid rate of 65 speed, because of the direct connection of

the rope 206 with the drum 231 which is mounted directly on the shaft 76, with no reduction gearing intervening.

After the operation of severing a block of material from the mine wall and of loading the same into a mine car has been performed, it is necessary to return the belt 110 to initial position preparatory to producing another cut in the mine wall. In order to restore the parts to initial position rapidly, 70 I provide a clutch 244 opposite that designated 100 on the shaft 76, so that after the clutch 235 is released, the lever 102 may be operated to effect transmission of power from the shaft 76 to the sprocket 245, as 75 shown in Figs. 1 and 5. This sprocket 245 is geared by a sprocket chain 246 directly to the drum 60 without the intervention of the reduction gearing 63, 64, 66 and 67 shown in Fig. 2. As soon as the belt approaches the chain cutter frame, the clutch 243 may be thrown to released position and then the clutch 100 thrown in by proper movement of the manual lever 102 (Fig. 2), whereupon the motion of the belt will be 80 continued but at a much slower rate of speed, until the stop 111 strikes against the plates 112, 113, whereupon further motion of the rope 56 relatively to the pulleys 50, 53 and segmental plate 46 will be discontinued, but further pull on the rope 56 will start feeding the chain cutter forward again. At such time the chain cutter is 85 always operating, because whenever the electric motor operates the chain cutter is 90 also operated through the sprocket 149. Furthermore, in order to assure that the chain cutter will always be operated in the proper direction, I prefer to omit from the controller box 99 a reversing switch, although one may be provided for initial connection of the motor to the supply means in the proper direction and thereafter a controller comprising the usual starting rheostat relied upon to always start up the motor in the same direction. 95 100 105 110

The apparatus as shown in Figs. 2 and 5 also makes provision for moving the mining machine laterally in either direction. For this purpose two windlass drums 247 and 248 are keyed to the shaft 76 so as to rotate therewith. Ropes indicated by the dotted lines 249 and 250 may be guided around the pulleys 251 and 252 respectively, which are mounted on brackets 253 and 254 connected 115 to the cross angle-beam 25. The rope 250 may be extended to a suitable anchorage in the mine at one side of the mining machine and the rope 249 may be extended to a suitable anchorage at a suitable distance from 120 the other side of the mining machine. The rear ends of the ropes 249 and 250 may be guided over the pulleys 255 and 256 pivoted in suitable position on the cross angle-beam 23, as shown in Figs. 2 and 3. By looping 125 130

the ropes 249 and 250 one or more times about drums 247 and 248 respectively, either drum may transmit power to the rope thereon whenever desired. For instance, if 5 the rope 249 is anchored at a suitable distance from one side of the mining machine, power may be transmitted to the rope 249 to pull the mining machine laterally when the rear end of the rope 249 is pulled manually 10 to tighten the loops on the drum 247. In a similar manner by pulling back on the rope 250 its loops may be tightened on the drum 248 so that the mining machine may be pulled in the opposite direction. By an- 15 choring the rear ends of either or both ropes 249 and 250 and partly looping the ropes around the drums 247 and 248, and exerting suitable pulls on the lateral extensions of the ropes, the mining machine 20 may be shifted toward the rear by the electrically operated power mechanism. In order to shift the mining machine forward, the lateral extensions of the rope may be guided around direction anchorages before 25 being secured to fixed anchorages, toward the front of the mining machine. In such case, by properly looping ropes 249 and 250 around the drums 247 and 248 respectively, and exerting suitable pulls on the rear por- 30 tions of the ropes, the entire mining machine may be moved forwardly on the skids 175 and 175' by electric power mechanism. As shown in Fig. 1, pulleys 255 and 256 (Fig. 2) may be keyed to a square ended shaft 257 35 so that a crank may be applied to turn the pulleys 255 and 256 and thus exert a pull on either rope 249 or 250 as desired, to secure the proper frictional connection between the same and the windlass drum 247 or 248. 40 Also as indicated in Fig. 1, the pulley blocks for the guide pulleys 251 and 252 may be pivoted and located opposite openings 258 in the lower longitudinal beams 22, 22' of the main frame of the mining ma- 45 chine. Individual operation of the drums 255 and 256 may be secured by not permanently connecting the ropes 249 and 250 thereto but relying upon wrapping the ends of such rope around the drum to secure op- 50 erating connection in a well-known manner.

It should be observed that in some instances the feeding operation of the loop chain cutting mechanism may be continued beyond the point where the block of material 55 is entirely severed from the mine wall, so that the pawls 122 may snap over and above the cut out section of material. This will effect the direct and positive engagement of the pawls with the material, so that when 60 the belt 110, together with the cutting mechanism, is retracted, the material will be drawn back in a very positive manner. However, in most instances, it would be preferred to rely on the pawls 122 digging into 65 the cut material upon reverse movement

thereof so as to cause backward movement of the material from the mine wall.

Obviously, those skilled in the art may make various changes in the details and arrangement of parts without departing from 70 the spirit and scope of my invention as defined by the claims hereto appended; I desire, therefore, not to be restricted to the exact construction disclosed in the drawings and in the foregoing description. 75

What I claim, and desire to have protected by Letters Patent of the United States:—

1. The combination with a main frame, of a supplemental frame pivoted thereto, 80 core cutting mechanism having an unobstructed core opening therethrough carried by said supplemental frame, a bracing member pivoted to said main frame, a screw-threaded rod pivoted to said supplemental frame, and two nuts on said screw-threaded rod cooperating with said bracing member to adjust the position of said supplemental frame and hold the same in ad- 85 justed position. 90

2. The combination with cutting mecha- nism, of means for operating the same, a frame for said cutting mechanism, a rope frictionally connected to said frame, winding apparatus connected to one end of said 95 rope, a conveyer belt connected to the other end of said rope, and power mechanism connected to the other end of said belt. 100

3. The combination with cutting mecha- nism, of means for operating the same, a 100 frame for said cutting mechanism, a rope frictionally connected to said frame, means for exerting a pull on one end of said rope to feed said cutting mechanism, a conveyer connected to the other end of said rope, 105 means for limiting the movement of said conveyer toward said frame, and means for exerting a pull on the other end of said conveyer to return the cutting mechanism to initial position and continue the motion 110 of said conveying mechanism toward the rear after said frame reaches its initial position. 115

4. The combination of cutting mechanism having an unobstructed core-opening there- 120 through, means for operating the same to cut a core, a frame for said cutting mecha- nism, power mechanism for operating said frame to feed said cutting mechanism, a clutch for effecting the operation of said feeding mechanism, mechanism for restoring said cutting mechanism to initial position, a clutch for effecting the operation of 125 said restoring mechanism, and an interlock between said clutches to prevent both from being thrown in simultaneously. 130

5. The combination with cutting mecha- nism having an unobstructed core-opening therethrough, of means for operating the same to cut a core, means for feeding said

cutting mechanism, a clutch for controlling said feeding means, means for restoring said cutting mechanism to initial position, an additional clutch for controlling said restoring means, and an interlock to prevent both clutches from being thrown in simultaneously.

6. The combination with cutting mechanism having an unobstructed core-opening therethrough, of means for operating the same to cut a core, mechanism for moving said cutting mechanism in one direction, a clutch for controlling such moving mechanism, means for moving said cutting mechanism in the opposite direction, an additional clutch for controlling said last named means, and an interlock between said clutches to prevent one of them from being thrown in when the other is not.
- 10 7. A mining machine comprising core-cutting mechanism, power transmitting mechanism connected thereto, a clutch for controlling the operation of said power transmitting mechanism, additional power transmitting mechanism, an additional clutch for controlling said additional power transmitting mechanism, and a mechanical interlock between said clutches.
- 15 8. A mining machine comprising a motor, a shaft, driving gear between said motor and said shaft, cutting mechanism, feeding means connected between said cutting mechanism and said shaft, a clutch on said shaft for controlling said feeding means, loading apparatus, means for operating said loading apparatus from said shaft, an additional clutch for controlling said operating means, and a mechanical interlock between said clutches for preventing the operation of one when the other is thrown in.
- 20 9. The combination with cutting mechanism comprising a swinging frame, a rope associated with said frame, apparatus for exerting a pull on one end of said rope to swing the said cutting mechanism in feeding direction, loading apparatus connected to the other end of said rope, apparatus for operating said loading apparatus, a clutch for controlling said operating apparatus, an additional clutch for controlling the aforesaid apparatus for exerting a pull on said rope to move the cutting mechanism in feeding direction, and a mechanical interlock between said clutches to prevent one from being thrown in when the other is in operating position to assure freedom of movement of one end of said rope when a pull is being exerted on the other end thereof.
- 25 10. A mining machine, comprising power transmitting apparatus, a clutch for controlling said power transmitting apparatus, additional power transmitting apparatus, an additional clutch for controlling said additional power transmitting apparatus,

operating levers, one for each of said clutches, a perforated bracket, a bar pivoted at one end to one of said operating levers and having its other end extending into the perforation in said bracket, a perforated fulcrum block carried by the other operating lever with the perforation therein registering with the perforation in said bracket when the clutch near the same is in released position, whereby the rod extending through both perforations when the other clutch is operated will lock the clutch adjacent said perforated block against being moved to operative position.

11. A mining machine, comprising cutting mechanism, means for operating the same, feeding apparatus for said cutting mechanism, a clutch for controlling said feeding apparatus, an operating lever for said clutch, a perforated fulcrum block connected to and movable with said operating lever, a perforated bracket having its perforation registering with the perforation in said fulcrum block when said clutch is in released position, means for restoring said cutting mechanism to initial position, a clutch for controlling said restoring means, an operating lever for said last named clutch, a rod having one end fitting into, the perforation in said bracket and connected to said last named clutch to move therewith to effect movement of the other end of said rod into the perforation in said fulcrum block when said last named clutch is moved to operative position, said fulcrum block preventing movement of said last named clutch to operative position when the first named clutch is in operative position.

12. In combination, a cutter frame, a conveyer belt, a connection between said cutter frame and conveyer belt, means for moving said cutter frame into a kerf in a mine wall and dragging said belt into said kerf, stops carried by said belt and arranged to lie in the same plane as said belt when the latter is moved in one direction, and to be moved out of said plane when said belt is moved in the reverse direction, and means for pulling said belt to restore said frame to initial position and cause said stops to be moved out of the plane of said belt.

13. In a mining machine, the combination with loop chain core-cutting mechanism having an unobstructed core opening therethrough, of feeding mechanism therefor, and mechanism comprising a pawl movable with said cutting mechanism freely into the kerf produced thereby in the feeding direction but engaging the cut material upon the discontinuance of said feeding mechanism when gravity is free to act tending to return said cutting mechanism toward initial position.

14. A mining machine comprising a sup-

- porting frame, cutting mechanism, means for operating the same, mechanism for feeding said cutting mechanism, and means on said frame comprising a pawl freely movable in feeding direction but engaging the cut material when said cutting mechanism moves or tends to move in reverse direction. 65
15. A mining machine comprising a supporting frame, a kerf cutter mounted thereon, means for operating the same, mechanism for feeding said kerf cutter, and means comprising a pawl mounted on said frame in position to be freely movable with said kerf cutter into the kerf produced thereby, 70 and operating automatically to grip the cut material when the kerf cutter moves in reverse direction.
16. A mining machine, comprising a supporting frame, kerf cutting mechanism mounted thereon, means for operating the same, apparatus for feeding said kerf cutting mechanism, and a plurality of spring pressed pawls arranged on said frame in position for freely entering said kerf with said kerf cutting mechanism but gripping the cut material upon reverse movement of said kerf cutting mechanism. 75
17. The combination with a supporting frame, of a loop chain cutter thereon for entirely severing from a mine wall an upright section of material, means for operating said cutter, mechanism for feeding said cutter during its operation, mechanism comprising resilient means on said frame in position for freely entering said kerf while said cutter is being fed forward, but engaging said cut material when the cutting mechanism is moved in reverse direction to compel the cut material to move back therewith. 80
18. The combination with a supporting frame, of kerf-cutting mechanism thereon, means for operating the same, apparatus for feeding said kerf-cutting mechanism, means on said frame in position for freely entering the kerf in feeding direction of said kerf-cutting mechanism for expansion to grip the material when said feeding apparatus is discontinued in its operation, and power mechanism applied to said gripping means to dislodge the cut material from the mine wall. 85
19. The combination with a kerf-cutter, of a frame for supporting the same, means for operating said kerf-cutter, mechanism for feeding said kerf-cutter during its operation, a plurality of spring-pressed pawls spaced apart from each other and movable with said frame freely into the kerf produced by said kerf-cutter, and means for actuating said frame in reverse direction to cause said pawls to engage the cut material and move the same back with said frame. 90
20. In a mining and loading machine, the combination with a supporting frame, of kerf cutting mechanism mounted thereon, loading apparatus mounted on said supporting frame to extend to the rear end thereof, a rope connected to said loading apparatus, means for exerting a pull on said rope, and mechanism for guiding said rope to effect the feeding of said kerf cutting mechanism when said rope pulling means is operated. 95
21. The combination with cutting mechanism, of means for operating the same, a frame for supporting said cutting mechanism, a rope associated with said frame and movable in either direction thereon, loading apparatus connected to one end of said rope, power mechanism applied to the other end of said rope, and an abutment to limit the movement of said rope relatively to said frame when said power mechanism is operated, to secure feeding movement of said cutting mechanism. 100
22. The combination with cutting mechanism, of a frame supporting the same, means for pivotally supporting said frame, a rope, guiding mechanism carried by said frame for directing the rope to one side of said pivotal support opposite the cutting mechanism, power operating mechanism applied to one end of said rope, and loading apparatus connected to the other end of said rope. 105
23. A mining machine comprising cutting mechanism, a frame carrying said cutting mechanism, means for pivotally supporting said frame, a rope, winding apparatus connected to one end of said rope, a curved segmental guide fixed to said frame for receiving said rope, two pulleys mounted on said frame in proximity to said segmental guide, 110 a rope guide at the lower portion of said frame, an additional rope guide pivoted to the lower portion of said frame, loading apparatus connected to the other end of said rope, and power mechanism for operating said loading apparatus while moving said rope over said rope guide, whereby when said rope winding apparatus is operated said loading apparatus is restored to initial position. 115
24. A mining machine comprising cutting mechanism, a frame carrying said cutting mechanism, rope guides carried by said frame, a rope associated with said rope guides and movable around the same in either direction, loading apparatus connected to one end of said rope, means for operating said loading apparatus and pulling said rope around said rope guides while said frame is held stationary in initial position, 120 and winding apparatus connected to the other end of said rope for exerting a pull thereon to restore said loading apparatus to initial position and thereafter effect forward feeding operation of said cutting mechanism. 125
25. A mining machine comprising cutting mechanism, a frame carrying the same, rope

guides on said frame, a rope associated with said rope guides and movable around the same in either direction, a conveyer connected to one end of said rope, means for limiting the movement of said conveyer toward said frame, apparatus for operating said conveyer and pulling said rope around said guides while said frame is held stationary in initial position, and winding apparatus connected to the other end of said rope for exerting a pull thereon to restore said conveyer to initial position while said rope moves around said guides and, after said limit means is reached, effecting feeding operating of said cutting mechanism.

26. A mining and loading machine comprising core cutting mechanism, loading apparatus for taking the material from said core cutting mechanism, said loading apparatus comprising a chute having a forward portion inclined upwardly and rearwardly from the initial position of said core cutting mechanism, said chute also having a rearwardly extending pivotal portion adapted to overhang a mine car on a track back of the mining and loading machine, and means for adjusting the height of the rear end of said pivotal portion of said chute.

27. A mining and loading machine comprising supporting framework, core cutting mechanism having an unobstructed core opening therethrough and mounted on the forward end of said framework to swing forwardly and upwardly on a horizontal axis, loading apparatus comprising means for receiving the core material from said core cutting mechanism and transferring such material upwardly and rearwardly to a rearwardly extending section pivoted on said framework, and means for adjustably holding said rearwardly extending section in position to direct the loading of the material into a mine car.

28. A mining machine comprising a supporting frame, cutting mechanism mounted thereon, a flexible conveyer belt mounted on said frame in position for receiving dislodged material from said cutting mechanism at the mine wall, guide rollers at the rear end of said frame, apparatus for actuating said belt to move the material thereon toward loading position, and apparatus connected to the other end of said belt to restore the same to initial position on said frame in relation to said cutting mechanism and thereafter effect feeding movement of said cutting mechanism.

29. A mining machine comprising a loop chain core cutter having an unobstructed core opening therethrough, a pivoted frame for supporting said core cutter, means for operating said core cutter including the feeding thereof, a supporting frame for mounting said pivoted frame to swing on

a horizontal axis, and a curved plate concentric with said axis and supported a short distance from the latter.

30. A mining machine comprising a loop chain cutter, a swinging frame carrying said loop chain cutter, a shaft for supporting said frame, a curved plate concentric with said shaft and supported by said frame a short distance from said shaft, a guide for the chain cutter mounted at one end of said curved plate, operating mechanism for said chain cutter located at the other end of said curved plate and supported partly thereby and partly by said frame, and means for slowly swinging said frame in feeding direction.

31. The combination with a loop chain cutter, of means for operating the same, power mechanism including reduction gearing for slowly feeding said loop chain cutter forward during its cutting operation, loading apparatus, means for operating said loading apparatus, and means for connecting direct gearing in place of said reduction gearing and operating said feeding mechanism to quickly restore said loading apparatus to initial position.

32. A mining machine comprising cutting mechanism, a rope associated therewith, a winding drum connected to one end of said rope, reduction gearing and direct gearing associated with said winding drum, a double clutch, means for throwing said clutch to effect the operation of said reduction gearing to cause the feeding operation of said cutting mechanism, loading apparatus connected to the other end of said rope, and means for operating said loading apparatus, said direct gearing effecting the quick return of said loading apparatus to initial position when said clutch is thrown in the opposite direction.

33. In a mining machine, the combination with mechanism for cutting a crescent-shaped core in a mine wall in one operation, of feeding mechanism therefor, mechanism comprising a pawl movable with said cutting mechanism freely into the kerf produced by said cutting mechanism but engaging said cut material upon the discontinuance of said feeding mechanism, and means for supporting said cutting mechanism to cause the same to tend to return toward initial position by gravity.

34. In a mining and loading machine, the combination with a supporting frame, of core cutting mechanism mounted thereon to swing on a horizontal axis, said core cutting mechanism having an unobstructed core opening therethrough for the passage of an upright core of material, means for operating said core cutting mechanism to sever an upright section of material from a mine wall in advance of

- 5 said frame, flexible means connected to said core cutting mechanism and entering the mine wall therewith, and mechanism for operating said flexible means to cause the same to move the severed section of material 10 back from the mine wall and by continued movement transfer the severed section toward loading position.
- 10 35. In a mining and loading machine, the combination with a supporting frame, of an inclined runway on said frame, loop chain core cutting mechanism mounted at the forward end of said runway in position to cut an upright core of material in advance of 15 said frame, means mounted on said frame for driving said core cutting mechanism, a cable extending to and from said core cutting mechanism, and means connected to the ends of said cable for feeding said core cutting mechanism and restoring the same to approximately initial position.
- 15 36. In a mining machine, the combination with supporting framework, of core cutting mechanism, having an unobstructed core 20 opening therethrough and pivoted to said framework for swinging feeding movement, means for driving said core cutting mechanism, a single rope connected to said core cutting mechanism, and means mounted on 25 said framework for exerting pulls on the ends of said rope to swing said core cutting mechanism in both directions to effect feeding movement thereof and restoration to 30 initial position.
- 30 35. 37. In a mining and loading machine, the combination with cutting mechanism comprising a cutter frame, of a rope frictionally connected to said cutter frame, conveyer mechanism connected to one end of said 35 rope, means connected to the other end of said rope to exert a pull thereon, and power mechanism connected to that end of the conveyer mechanism remote from its connection to said rope.
- 35 45. 38. A mining machine comprising cutting mechanism, means for operating the same, apparatus comprising a rope for feeding said cutting mechanism, a rope drum connected to one end of said rope, driving mechanism for said rope drum, a clutch for controlling said driving mechanism, an operating lever for said clutch, an additional winding drum connected to the other end of said rope, additional driving mechanism 50 for said additional rope drum, an additional clutch for controlling said additional rope drum, an additional operating lever for said additional clutch, interlocking mechanism between said clutches to prevent either 55 from being thrown in when the other is connected to its respective rope drum driving mechanism, and means for transmitting power to said rope drum driving mechanisms whereby under the control of said clutches 60
- 65 said cutting mechanism may be positively moved in one direction to feed the same and positively moved in the opposite direction to restore the same to initial position.
- 70 39. In a mining machine, the combination with kerf cutting mechanism comprising a cutter frame, of dislodging mechanism connected to said cutter frame and comprising a pivoted pawl movable freely along said kerf in feeding direction back of said kerf cutting mechanism, and means for exerting 75 a pull on said dislodging mechanism in the opposite direction to cause the same to engage the cut material and dislodge the same from the mine wall.
- 80 40. In a mining and loading machine, the combination with a supporting frame, of kerf cutting mechanism mounted thereon, dislodging mechanism, a rope connected to said dislodging mechanism and guided on said kerf cutting mechanism for movement 85 relatively thereto, means for exerting a pull on said rope to move said dislodging mechanism into proximity to said kerf cutting mechanism and thereafter effect the feeding movement of said kerf cutting mechanism, 90 and means for exerting a pull on the said dislodging mechanism to dislodge the cut material from the mine wall while restoring said kerf cutting mechanism to initial position and continuing the movement of said 95 dislodging mechanism after said kerf cutting mechanism has been restored to initial position, said rope then moving relatively to said kerf cutting mechanism.
- 100 41. In a mining machine, the combination with kerf cutting mechanism comprising a cutter frame, of a rope, guiding mechanism carried by said frame for directing movement of said rope relatively to said frame, power operating mechanism applied 105 to one end of said rope, and dislodging mechanism connected to the other end of said rope.
- 110 42. In a mining machine, the combination with a supporting frame, of cutting mechanism comprising an open frame pivoted to said supporting frame to swing about an axis transverse to the vertical and longitudinal axes of the machine, means for operating said cutting mechanism to cut forward and upward, and adjustable means for limiting the movement of said open frame in a direction reverse of the feeding direction.
- 115 43. In a mining machine, the combination with a supporting frame, of conveying mechanism mounted on said frame in fixed relation thereto, cutting mechanism mounted on said frame to swing about an axis transverse to the vertical and longitudinal 120 axes of the machine, a connection between said cutting mechanism and said conveying mechanism to cause the latter to move with
- 125

the cutting mechanism beneath the dislodged material, means for operating said cutting mechanism including swinging feeding movement thereof while said conveying mechanism remains in fixed relation to said supporting frame, and means for swinging the rear portion of said conveying mechanism about another axis transverse to the vertical and longitudinal axes of the machine at a distance above the floor of the mine.

44. In a mining machine, the combination with kerf-cutting mechanism, of a conveyer belt connected thereto and adapted to enter a kerf therewith, means for pulling said belt while restoring said kerf-cutting mechanism to initial position, and means operated by said kerf-cutting mechanism upon being restored to initial position to permit said belt to continue movement in the same direction.

45. In a mining machine, the combination with a supporting frame, of loop chain core-cutting mechanism having an unobstructed core opening therethrough and mounted on said supporting frame to swing about an axis transverse to the vertical and longitudinal axes of the machine, conveying mechanism on said supporting frame in position to extend to the lower end of the cut body of material, and means for adjusting the position of the rear end of said conveying mechanism.

46. In a mining and loading machine, the combination with a supporting frame, of conveying mechanism mounted on said supporting frame to extend from a lower receiving position at the forward portion of said frame to an upper delivery position at the rear end of said frame, means for adjusting the position of the rear end of said conveying mechanism, and loop chain core-cutting mechanism having an unobstructed core opening therethrough and mounted for swinging feeding movement on a horizontal axis at the forward portion of said supporting frame in position to deliver dislodged material from the mine wall to the forward receiving portion of said conveying mechanism.

47. In a mining machine, the combination with a supporting frame, of a loop chain core cutter having an unobstructed core opening therethrough and comprising an endless cutter chain, means for supporting said loop chain core cutter at adjusted elevations for swinging feeding movement on a horizontal axis on said supporting frame, mechanism comprising a pawl movable with said cutting mechanism freely into the kerf produced thereby but engaging the cut material upon reverse movement of the cutting mechanism, and means for operating said loop chain core cutter.

48. In a mining machine, the combination with cutting mechanism, of a conveyer belt connected thereto and movable therewith, means for pulling said belt connections to effect the restoration of said cutting mechanism to initial position when said belt is pulled, and means operated by the restoration of said cutting mechanism to initial position to permit the continuation of movement of said belt after said cutting mechanism is returned to initial position.

49. In a mining machine, the combination with a pivoted cutter bar, of a conveyer, a cable secured to one end of said conveyer and variably connected to said cutter bar, and means acting on said cable for causing said conveyer to move with said cutter bar during movement of the latter about its pivot.

50. In a mining machine, the combination with a chute comprising a flexible belt extending horizontally in transverse directions in position for receiving blocks of material directly from their positions in the mine wall, and means for cutting an arcuate core of material in the mine wall in arcuate alignment with said chute.

51. In a mining and loading machine, the combination with a supporting frame, of chain core-cutting mechanism mounted thereon, means for driving said core-cutting mechanism, rope-winding mechanism mounted on said supporting frame and comprising two rope drums with ropes wound thereon, a flexible apron conveyer having its ends connected to the ends of said ropes, and connections between said core-cutting mechanism and one of said ropes to effect forward feeding of the core-cutting mechanism when sufficient pull is exerted on the said last-named rope.

52. In a mining and loading machine, the combination with a supporting frame, of a motor thereon, rope-winding mechanism connected to said motor, core-cutting mechanism, means for operating said core-cutting mechanism, a flexible apron conveyer, and ropes connected to said core-cutting mechanism and to said apron conveyer to operate the latter and effect feeding movement of said core-cutting mechanism.

53. In a mining and loading machine, the combination with a supporting frame, of core-cutting mechanism thereon, means for operating said core-cutting mechanism, a conveyer, and rope gearing for operating said conveyer and for feeding said core-cutting mechanism.

54. In a mining and loading machine, the combination with a supporting frame, of kerf-cutting mechanism mounted thereon, means for driving said kerf-cutting mechanism, a conveyer, and means composed entirely of rope gearing for operating said

conveyer and for feeding said kerf-cutting mechanism.

55. In a mining machine, the combination with cutting mechanism, of means for operating said cutting mechanism to entirely cut out from a mine wall a section of material, means following said cutting mechanism to extend under a section of material as it is being cut in position for receiving the cut material from above, and means for operating said receiving means to cause the same to carry into loading position the section of material resting freely by gravity thereon.
56. In a mining machine, the combination with a supporting frame, of loop chain core-cutting mechanism mounted on the forward end of said frame to swing on a horizontal axis, means for operating said loop chain core-cutting mechanism to cut an upright crescent-shaped core in a mine wall in advance of said frame, a flexible apron adapted to move along the kerf back of the core of material, rope connections for holding the forward end of said apron near the rear of said loop chain core-cutting mechanism during the feed thereof to effect the dragging of said apron along the kerf back of said core, means for exerting a pull on the rear end of said apron to move the same back and restore said core-cutting mechanism to initial position, mechanism for discontinuing the rearward pull on said cutting mechanism when the latter reaches initial position while the rearward movement of said apron continues to move the dislodged material carried thereby to loading position, and means for restoring the forward end of said apron to its position near the rear of said core-cutter for another mining and loading operation.
57. In a mining and loading machine, the combination with a frame having a chute extending longitudinally thereof and inclined forwardly to the mine floor and extending rearwardly to overhang a mine car, of loop chain core-cutting mechanism mounted to swing forwardly in advance of said frame and in advance of said chute on a horizontal axis on the forward end of said frame, means for operating said loop chain core-cutting mechanism to cut an upright crescent-shaped core in the mine wall in advance of said frame, a flexible carrier adapted to span the space between the forward open end of said chute and the rear surface of said core in position to receive the material as it is dislodged, and means for operating said flexible receiving means to carry said dislodged material along said chute to the rear open end thereof for loading into mine cars and reversing the movement of said flexible receiving means along said chute back to its receiving position in advance of said chute.
58. In a mining and loading machine, the combination with a frame having a longitudinal bed plate, of kerf-cutting mechanism mounted on the forward end of said frame for operation in advance thereof to cut a core of material in the mine wall, flexible receiving means movable back and forth along said bed plate, means for connecting said receiving means to said kerf-cutting mechanism to draw said receiving means into the kerf back of the core, and mechanism connected to the forward end of said receiving means to grip the core on its reverse movement of said receiving means to compel the core to move back with the receiving means and prevent sliding of the receiving means under said core, and means for operating said receiving means to move the same along said bed plate to transfer the cores toward loading position.
59. The combination with a supporting frame, of kerf-cutting mechanism thereon, means for driving the same, apparatus for feeding said kerf-cutting mechanism, and means on said frame in position for freely entering the kerf in feeding direction of said kerf-cutting mechanism for expansion to grip the material when said feeding apparatus is discontinued in its operation, the return of said feeding apparatus acting as power mechanism applied to said gripping means to dislodge the cut material from the mine wall.
60. In a mining machine, the combination with a frame, of a chute mounted thereon, means for delivering material into the receiving end of said chute, and gripping devices connected to and moving with said delivering means freely in one direction but gripping the material to move the same toward the delivery end of said chute when additional material is being delivered into the receiving end of said chute.
61. The combination with a loop chain cutter, of means for operating the same, mechanism for feeding said loop chain cutter to entirely sever a section of material from the mine wall, mechanism freely movable into the kerf produced by said cutter while moving in feeding direction, for digging into and gripping the cut section of material when the feeding operation is discontinued, and means for actuating said cutter bodily in the reverse direction causing the cut section of material to move back with the same.
62. In a mining and loading machine, the combination with a frame having a rear horizontal portion adapted to overhang a mine car and a forward downwardly inclined portion adapted to extend to receiving position adjacent the base of a mine wall, of means mounted on the forward end of said frame for dislodging material from an upright mine wall in advance of said

frame and to a position at the base of the mine wall in advance of the forward open end of the chute, and mechanism extensible beyond the forward open end of said chute

5 for catching, carrying and transferring dislodged material from the mine wall to the mine car under the overhanging rear portion of said chute.

In testimony whereof I have signed my name to this specification, in the presence of 10 two subscribing witnesses, on this 10th day of July, A. D. 1915.

EDMUND C. MORGAN.
